UNITED STATES PATENT OFFICE.

CHARLES D. LANNING, OF BOSTON, MASSACHUSETTS.

SHIPPER-RELEASING MECHANISM FOR ELECTRICALLY-CONTROLLED WARP STOP MECHANISM.

1,000,418.

Specification of Letters Patent. Patented Aug. 15, 1911.

Application filed December 30, 1905. Serial No. 293,933.

To all whom it may concern:

Be it known that I, CHARLES D. LANNING, a citizen of the United States of America, residing at Boston, in the county of Suffolk 5 and Commonwealth of Massachusetts, have invented certain Improvements in Shipper-Releasing Mechanism for Electrically-Controlled Warp Stop Mechanism, of which the following is a specification.

10 The invention relates to mechanism for releasing the shipper-lever in electrically controlled warp-stop-mechanism in looms, without the intervention of any "going" part of the loom, and consists of a magnet 15 in the circuit which includes the drop-bar terminals, and mechanism connected with the armature of the magnet, which mechanism acts directly to release the shipper-lever when the circuit is closed by 20 the contact of a drop-bar with terminals of opposite polarity; and the invention further consists in a cut-out for the drop-bar terminals, which is operated by the magnet when a drop-bar closes the circuit, 25 and by the same operation closes a short circuit through the magnet and electrical generator in order to give increased energy to the magnet to operate the shipper-lever. A solenoid magnet is found preferable for the 30 purpose as it gives greater range of motion and is the form of magnet illustrated in the accompanying drawings, and wherein the movable core is intended to be included in the general term armature.

35 In the drawings, Figure 1 is a side elevation of a solenoid magnet, and the combined cut-out for the drop-bar circuit and switch for the short circuit; Fig. 2 is an elevation of the end of a loom-frame, showing the 40 shipper-lever, the magnet, the mechanism operated thereby to release the shipper, and the electric circuit; Fig. 3 is an elevation of the drop-bars and their contact terminals, the lease-rods and warp-threads which 45 normally support the drop-bars; the lease-rods and terminals are in section; Fig. 4 is a diagrammatic view of the improvements, with the circuits, the drop-bars, their electric terminals, the magnet, shipper-lever and mechanism to release it.

50 Referring by designating characters to the parts illustrated in the drawings, A is the loom-frame, S the shipper-lever, M the magnet, preferably mounted upon the loom frame and here shown as a solenoid and pro-

vided with a core m' ; e a lever pivoted to the frame A at e' . The long end of this lever is pivoted to the outer end of the core m' , and the short end thereof is so located in reference to the shipper-lever S that 60 when the core m' is drawn into its magnetic coil, the swing of the lever l will push the shipper from its retaining notch.

C is the circuit wire, extending from the generator G to the magnet M, the terminals 65 t t' and the drop-bars d which are normally supported out of contact with the terminals by the warp-threads w .

B is the cut-out, and short circuit switch, 70 which makes contact with terminals b^2 , b^3 and which is attached to and operated by the armature E pivoted at e' . The armature E is controlled by the stationary part m^2 of the core of the magnet M.

In Fig. 4, C indicates the circuit closed by 75 the drop-bars, and C' indicates the circuit closed by the switch B.

F (Fig. 4) is a spring with which the shipper S makes contact to close the circuit when in its retaining notch, and with which 80 it breaks contact when released from the notch. In Fig. 2, H is the belt shifting or clutch releasing lever operated by the shipper S when it is released.

The operation of these improvements will 85 be readily understood by reference to Fig. 4. When a warp-thread breaks or becomes abnormally slack, a drop-bar d falls and closes the circuit C by making contact with the two terminals t t' ; this energizes the magnet M and causes the armature E to be drawn to the core m^2 , thereby withdrawing the switch arm B from the contact b^2 and transferring it to the contact b^3 , thus cutting 90 out the circuit C and switching in the short circuit C', by which a stronger current will pass through the coils of the magnet M and draw in the core m' , which will carry the long end of the lever l with it and cause the short end of the lever l to release the shipper S from its retaining notch.

By positively cutting out the circuit C and substituting the short circuit C', I prevent such loss or dissemination of current as would occur were merely a shunt circuit provided, since in practice the current would not be absolutely confined to such shunt circuit, and hence the current available in such case to operate the armature would be correspondingly weakened. When the shipper is re- 100 105 110

leased it will break the circuit at the spring F and the switch arm B will be returned to its normal position by a spring I.

Attempts have been made to release the shipper-lever by employing the shipper as the armature of the magnet, but this has proved impracticable, because the same force that is employed to release the shipper-lever tends to hold it; and this disadvantage is intensified because of the strength of current required in a magnet designed to work in such a direct manner.

I claim:

1. In a loom provided with a shipper lever and its retaining means, electrical warp-stop-mechanism consisting of a magnet, an armature therefor, lever mechanism connected with and operated by the armature, which mechanism acts directly to eject the shipper-lever from its retaining means, a pair of terminals of opposite polarity, drop-bars normally supported by the warp-threads and adapted to coöperate with the terminals to close an electric circuit, when the drop-bars are not thus normally supported, and an electric circuit which includes the said magnet and terminals.

2. In a loom, electrical warp-stop-mechanism consisting of a magnet secured to the loom-frame, an armature therefor, means connected with the armature which act directly to release the shipper when the armature is operated, drop-bars normally supported by the warp-threads, a pair of terminals of opposite polarity, in proximity to the drop-bars and adapted to be connected by the fall of a drop-bar when released by a warp-thread, an electric circuit which includes said magnet and terminals, and a cut-out for the terminals which is operated by the magnet when the circuit is closed by a drop-bar.

3. In a loom, electrical warp-stop-mechanism consisting of a magnet secured to the loom-frame, an armature for the magnet, means connected with the armature which act directly to release the shipper when the armature is operated by the magnet, drop-bars normally supported by the warp-threads, terminals of opposite polarity with which the drop-bars are adapted to coöperate to close an electric circuit, when they are not normally supported by the warp threads, an electric circuit which includes the said magnet and terminals, a cut-out for the circuit closed by the drop-bars, which cut-out is operated by said magnet, and a short circuit which is established through the magnet when the cut-out is operated.

4. In a loom, electrical warp-stop-mechanism consisting of a solenoid magnet, means connected with the core of the magnet which act directly to release the shipper, drop-bars normally supported by the warp-threads, terminals of opposite polarity in the path of movement of the drop-

bars when they are not normally supported by a warp-thread, which drop-bars when released by the thread are adapted to make contact with the terminals, an electric circuit which includes the said magnet and terminals, a cut-out for said circuit, which cut-out is operated by said magnet, and a short circuit which is established through the magnet when the cut-out is operated.

5. In a loom, electrical stop mechanism adapted to be actuated by a thread fault comprising a magnet, an armature therefor, shipper mechanism, operative connections between said armature and said shipper mechanism, an electric circuit including a pair of terminals of opposite polarity, means normally inactive to close said circuit in the absence of a thread fault but adapted to co-act with said terminals to close the circuit upon the occurrence of a thread fault, and a cut out for the said terminals, which is operated when the circuit is closed by said normally inactive means.

6. In a loom, electrical warp stop mechanism consisting of a magnet, an armature therefor, shipper mechanism, operative connections between said armature and said shipper mechanism, an electric circuit including a pair of terminals of opposite polarity, drop bars normally supported by the warp threads, but adapted to coöperate with the terminals to close the circuit upon the occurrence of a warp fault, and a cut out for the terminals which is operated when the circuit is closed by a displaced drop bar.

7. In a loom, electrical warp stop mechanism consisting of a main magnet, an armature therefor, shipper mechanism, operative connections between said armature and said shipper mechanism, an electric circuit including a pair of terminals of opposite polarity, drop bars normally supported by the warp threads, but adapted to coöperate with the terminals to close the circuit upon the occurrence of a warp fault, and a cut out for the terminals, said cut out being directly operated by the armature of said main magnet when the circuit is closed by a displaced drop bar.

8. In a loom, electrical warp stop mechanism consisting of a main solenoid magnet, an armature therefor, shipper mechanism, operative connections between said armature and said shipper mechanism, an electric circuit including a pair of terminals of opposite polarity, drop bars normally supported by the warp threads, but adapted to coöperate with the terminals to close the circuit upon the occurrence of a warp fault, and a cut out for the terminals, said cut out being directly operated by the armature of said main solenoid magnet when the circuit is closed by a displaced drop bar.

9. In a loom, electrical warp stop mecha-

nism consisting of an electric circuit containing but a single magnet, an armature therefor and a pair of terminals of opposite polarity, shipper mechanism, operative connections between said armature and said shipper mechanism, drop bars normally supported by the warp threads, but adapted to coöperate with the terminals to close the circuit upon the occurrence of a warp fault, 10 and a cut out for the terminals which is operated when the circuit is closed by a displaced drop bar.

10. In a loom, an electrical stop mechanism adapted to be actuated by a thread fault, comprising shipper mechanism, an electric circuit including a single magnet, an armature therefor, and a pair of terminals of opposite polarity, operative connections between said armature and said shipper mechanism, means normally inactive to close said circuit in the absence of a thread fault, but adapted to co-act with said terminals to close said circuit upon the occurrence of a thread fault, and means rendered operative by the closing of said circuit to render inactive that portion of the circuit that includes said terminals.

11. In a loom, electrical stop mechanism adapted to be actuated by a thread fault comprising shipper mechanism, an electric circuit including a single magnet mounted upon a stationary part of the loom, an armature therefor, and a pair of terminals of opposite polarity, operative connections between said armature and said shipper mechanism, means normally inactive to close said circuit in the absence of a thread fault, but adapted to co-act with said terminals to close said circuit upon the occurrence of a thread fault, and means rendered operative by the closing of said circuit to render inactive that portion of the circuit that includes said terminals.

12. In a loom, electrical warp stop mechanism consisting of an electric circuit including a magnet, an armature therefor and a pair of terminals of opposite polarity, shipper mechanism, operative connections between said armature and said shipper mechanism, drop bars normally supported by the warp threads but adapted to coöperate with the terminals to close the circuit upon the occurrence of a warp fault, and means rendered operative by the closing of said circuit to cut out that portion of the circuit that includes said terminals.

13. In a loom provided with shipper mechanism and retaining means therefor, electrical warp stop mechanism comprising a circuit including a magnet, an armature therefor and a pair of terminals of opposite polarity, warp drops normally supported by said warp threads but adapted to co-operate with the terminals to close the circuit upon the occurrence of a warp fault,

and connections whereby the movement of the armature upon energization of the magnet acts directly and instantaneously to operate said shipper mechanism, thereby to stop the loom without the interposition of a going part thereof.

14. In a loom, provided with shipper mechanism and retaining means therefor, electric warp stop mechanism comprising a circuit including a magnet, an armature therefor, and a pair of terminals of opposite polarity, lever mechanism between said armature and said shipper mechanism, warp drops normally supported by said warp threads but adapted to coöperate with the terminals to close the circuit upon the occurrence of a warp fault, the movement of the armature upon energization of the magnet acting directly and instantaneously to operate said lever mechanism between the armature and shipper mechanism, thereby to stop the loom without the interposition of a going part thereof.

15. In a loom provided with shipper mechanism and retaining means therefor, electrical warp stop mechanism comprising a circuit including a magnet mounted upon a stationary part of the loom, an armature therefor and a pair of terminals of opposite polarity, operative connections between said armature and said shipper mechanism, warp drops normally supported by said warp threads but adapted to coöperate with the terminals to close the circuit upon the occurrence of a warp fault, the movement of the armature upon energization of the magnet acting directly and instantaneously to operate said connections between the armature and shipper mechanism, thereby to stop the loom without the interposition of a going part thereof.

16. In a loom provided with shipper mechanism and retaining means therefor, electrical warp stop mechanism comprising a circuit including a solenoid magnet having a core armature and a pair of terminals of opposite polarity, warp drops normally supported by said warp threads but adapted to coöperate with the terminals to close the circuit upon the occurrence of a warp fault, and connections whereby the movement of the armature upon energization of the magnet acts directly and instantaneously to operate the shipper mechanism, to stop the loom without the interposition of a going part thereof.

17. A loom provided with shipper mechanism and retaining means therefor, electrical warp stop mechanism comprising a circuit including a magnet, an armature therefor and a pair of terminals of opposite polarity, lever mechanism between said armature and said shipper mechanism, said armature being positively connected to said lever mechanism, warp drops normally sup-

- ported by said warp threads but adapted to coöperate with the terminals to close the circuit upon the occurrence of a warp fault, the movement of the armature upon energization of the magnet acting directly and instantaneously to operate said lever mechanism between the armature and shipper mechanism, thereby to stop the loom without the interposition of a going part thereof.
- 10 18. In a loom provided with shipper mechanism and retaining means therefor, electrical warp stop mechanism comprising a circuit including a magnet, an armature therefor and a pair of terminals of opposite polarity, operative connections between said armature and said shipper mechanism, warp drops normally supported by said warp threads but adapted to coöperate with the terminals to close the circuit upon the occurrence of a warp fault, the movement of the armature upon energization of the magnet acting directly and instantaneously to operate said connections between the armature and shipper mechanism, thereby to stop the loom without the interposition of a going part thereof, and a cut out for the terminals which is operated when the circuit is closed by a displaced warp drop.
- 15 19. In a loom provided with shipper mechanism and retaining means therefor, electrical warp stop mechanism comprising a circuit including a magnet mounted upon a stationary part of the loom, an armature therefor, and a pair of terminals of opposite polarity, operative connections between said armature and said shipper mechanism, warp drops normally supported by said warp threads but adapted to coöperate with the terminals to close the circuit upon the occurrence of a warp fault, the movement of the armature upon energization of the magnet acting directly and instantaneously to operate said connections between the armature and shipper mechanism, thereby to stop the loom without the interposition of a going part thereof, and a cut out for the terminals which is operated when the circuit is closed by a displaced warp drop.
- 20 20. In a loom provided with shipper mechanism and retaining means therefor, electrical warp stop mechanism comprising a circuit including a solenoid magnet having a core armature therefor and a pair of terminals of opposite polarity, lever mechanism between said armature and said shipper mechanism and to which the core of said solenoid magnet is positively connected, warp drops normally supported by said warp threads but adapted to coöperate with the terminals to close the circuit upon the occurrence of a warp fault, the movement upon energization of the magnet acting directly and instantaneously to operate said lever mechanism between the armature and shipper mechanism, thereby to stop the loom without the interposition of a going part thereof.
- 25 21. In a loom provided with shipper mechanism and retaining means therefor, electrical warp stop mechanism comprising a circuit including a magnet, an armature therefor and a pair of terminals of opposite polarity, operative connections between said armature and said shipper mechanism, upon which operative connections the armature directly pulls when the magnet is energized, warp drops normally supported by said warp threads but adapted to coöperate with the terminals to close the circuit upon the occurrence of a warp fault, the movement of the armature upon energization of the magnet acting directly and instantaneously to pull upon said connections between the armature and shipper mechanism, thereby to stop the loom without the interposition of a going part thereof.
- 30 22. In a loom provided with shipper mechanism and retaining means therefor, electrical warp stop mechanism comprising a circuit including a magnet, an armature therefor and a pair of terminals of opposite polarity, lever mechanism between said armature and said shipper mechanism, upon which lever mechanism the armature directly pulls when the magnet is energized, warp drops normally supported by said warp threads but adapted to coöperate with the terminals to close the circuit upon the occurrence of a warp fault, the movement of the armature upon energization of the magnet acting directly and instantaneously to pull upon the said lever mechanism between the armature and shipper mechanism, thereby to stop the loom without the interposition of a going part thereof.
- 35 23. In a loom, an electrical stop mechanism adapted to be actuated by a thread fault comprising shipper mechanism, an electric circuit including a single magnet, an armature therefor and a pair of terminals of opposite polarity, operative connections between said armature and said shipper mechanism, means normally inactive to close said circuit in the absence of a thread fault but adapted to co-act with said terminals to close said circuit upon the occurrence of a thread fault, means rendered operative by the closing of said circuit to render inactive that portion of the circuit that includes said terminals, and means to break the circuit when the shipper mechanism is released.
- 40 24. In a loom, electrical warp stop mechanism comprising in combination a magnet, an armature therefor, shipper mechanism, means connected with the armature and acting directly upon the shipper mechanism to operate the same to stop the loom without the interposition of a going part thereof, a pair of terminals of opposite po-

larity, drop bars normally supported by the warp threads, but adapted to coöperate with the terminals to close the circuit upon the occurrence of a thread fault, and means rendered operative by the closing of said circuit to render inactive that portion of the circuit including said terminals.

25. Textile electrical stop mechanism comprising in combination a circuit having a magnet, shipper mechanism, means acting directly upon the shipper mechanism to operate the same without the intervention of

a going part, a pair of terminals of opposite polarity, drop bars normally thread supported but adapted to coöperate with the terminals to close the circuit upon the occurrence of a thread fault and means rendered operative by the closing of said circuit to render inactive that portion of the circuit including said terminals. 15
